UNITED STATES PATENT OFFICE.

EDWARD A. HEMPHILL, OF ELIZABETH, NEW JERSEY.

DESIGN FOR A CALENDAR AND INKSTAND HOLDER.

SPECIFICATION forming part of Design No. 21,587, dated May 31, 1892.

Application filed May 5, 1892. Serial No. 431,956. Term of patent 7 years.

To all whom it may concern:

Be it known that I, EDWARD A. HEMPHILL, a citizen of the United States, residing at Elizabeth, in the county of Union and State of New Jersey, have invented a new Design for a Calendar and Inkstand Holder, of which the following is a specification.

The leading feature of this design is a triangular inkstand-base with rounded corners and an inclined calendar-holder rising from the base and having rounded upper corners.

The design is shown in the accompanying drawings, in which—

Figure 1 is a plan view, and Fig. 2 an end elevation.

The shape of the inkstand-holding base *a* is triangular with rounded corners, as shown,

and the calendar-holder *b* is made with rounded upper corners, and it occupies an inclined position to the base at one side thereof, as shown, and there are openings in the holder for the calendar and clock.

What I claim is—

The design for a calendar and inkstand holder herein shown and described, the same comprising the triangular base with rounded corners and the inclined calendar-holder rising from the base and having rounded corners, as set forth.

Signed by me this 2d day of May, 1892.

EDWARD A. HEMPHILL.
